VACUUM CLEANERS

Bruno Eck, Cologne-Klettenberg, and Nikolaus Laing, Stuttgart, Germany, assignors, by mesne assignments, to Laing Vortex, Inc., New York, N.Y.

Filed Aug. 1, 1963, Ser. No. 299,301.

Claims priority, application Germany, Dec. 7, 1956, L 26,391.

14 Claims. (Cl. 15—347)

This invention relates to vacuum cleaners, and is a continuation-in-part of our earlier application No. 701,265 now abandoned, filed December 6, 1957. A vacuum cleaner comprises a motor-driven blower which sucks a stream of air through a so-called nozzle. In operation the nozzle is applied to a surface to be cleaned so that the dust thereon can be entrained in the air stream. The air is passed through means which separates the entrained dust from the air stream and collects this dust for subsequent removal.

The present invention, which aims to produce an improved form of vacuum cleaner, has regard to the following appreciations:

(a) The air stream has to produce a force on a dust particle which exceeds its weight and the force with which it adheres to the supporting surface. The force produced is, on a first approximation, dependent on the throughput (i.e., the volume of air aspirated per unit of time).

(b) In laminar flow there is always a boundary layer near stationary objects, in which the velocity is negligible. The dimensions of this layer are about those of the dust itself. Thus if the flow is laminar more suction must be applied to the nozzle than would be necessary according to (a) above had the flow been turbulent.

(c) The relatively massive blower and motor of vacuum cleaners hitherto known has either made them inconvenient and cumbersome objects to push around or has led to the blower being connected to the nozzle by a hose, which involves great pressure losses.

(d) The blowers previously used have their suction inversely related to the throughput. Where the blower is connected to the nozzle by a hose this has meant that the blower has had to produce pressures several times higher than what would have been necessary had the blower acted directly at the nozzle.

(e) The previously used blowers, operating in the range of low Reynolds numbers, are of low efficiency: they require to be driven at high speed to produce the required suction without being intolerably bulky, and this high speed makes such blowers noisy. A discussion of the operation of known blowers at low Reynolds numbers will be found in British specification No.: 876,611: this British specification however was not published at the date of the application of which this is a continuation-in-part.

In contrast to the vacuum cleaners known or proposed hitherto, it is strongly preferred, in carrying out the present invention to make use of a particular form of cross-flow blower, this blower (called hereinafter "tangential" blower) comprising a drum-shaped bladed rotor and guide means co-operating with said rotor to set up a cylindrical vortex when the rotor is rotated having a general characteristic of a Rankine vortex, which vortex is eccentric to the rotor axis and guides air twice through the path of the rotating blades in a direction transverse to the rotor axis.

It is to be understood that although cross-flow blowers were known since the turn of the century they never found favour commercially apparently on account of their unpredictable performance, prior to the development

of the "tangential" blower, certainly so far as the applicants are aware it has never hitherto been proposed to use a cross-flow blower in a vacuum cleaner.

The "tangential" blower has several advantages, chief of which is its ability to handle great volumes of air without being bulky or noisy: this enables the blower to be very small by comparison with what has hitherto been regarded as normal. However, the curve of pressure against volume drops sharply as the volume is reduced from a critical figure, e.g., by the nozzle becoming blocked. Now a vacuum cleaner, except in specialist applications, must be able to operate even if the nozzle is blocked: the fact that in the "tangential" blower pressure and throughput drop together from a critical value would appear to necessitate rejection of the blower for normal vacuum cleaner applications. However the invention provides a means of overcoming the problem: nozzle by-pass means are provided to enable air to flow to the rotor unaffected by the surface to be cleaned when the resistance to air flow through the nozzle rises above normal by reason of the conjunction of said surface with the nozzle whereby throughput of air through the rotor is maintained independent of air flow through the nozzle. Pressure is therefore maintained although the flow of air through the nozzle drops.

The by-pass can take various forms, as will be apparent from the following description. In certain rather special cases contemplated by the invention, as where the nozzle is formed between brushes, the nozzle provides its own by-pass in that air can pass through the bristles of the brushes to a sufficient extent even when the normal opening is blocked.

In the more usual cases where the nozzle is defined by rigid structure, a preferred by-pass means is a duct 35 adjacent the nozzle leading from ambient atmosphere to the suction side of the blower and so positioned as to direct air passing through the duct on to that portion of the surface to be cleaned which lies beneath the nozzle. When the mouth of the nozzle is blocked, sufficient air for the blower enters through the duct to maintain suction. Alternatively, the duct can be supplied with a portion of the air leaving the blower, rather than from the ambient atmosphere, and in this case it is the recirculation of air through the blower which enables suction to be maintained when the nozzle mouth is sealed.

Further forms of nozzle by-pass means provided by the invention include:

(a) A duct leading from the delivery side of the blower to the suction side and operative on slight fall of throughput to provide a recirculating air channel in circuit with the blower.

(b) A diffuser positioned at the outlet of the blower to receive air therefrom, said diffuser being perforated with the perforations in pressure communication with the suction side of said blower whereby air is removed by the boundary layer suction effect from within the diffuser and is recycled to the suction side of the blower. This by-pass means constitutes in effect a special case of (a) above.

(c) A duct opening on the suction side of said blower for passage of air from the ambient atmosphere to the blower and wherein the opening of said duct leading to said suction side opposes the direction of air flow from the nozzle to the blower, whereby under normal operating conditions the dynamic pressure of air moving from said nozzle to said blower opposes flow of air through said duct, and whereby when said dynamic pressure drops, air will flow through said duct to said blower.

The applicants have found that, unlike the hitherto commonly used blowers, the "tangential" blower is

sensitive to dust; that is its performance may drop sharply in a dusty environment. It is accordingly preferred, in accordance with the invention to arrange the filter means between the nozzle and the blower. It is a further preferred feature of the invention to mount a diffuser at the outlet of the blower, to enable the blower to produce sufficient pressure to suck air through the filter in the required volume.

According to a different aspect of the invention it provides a vacuum cleaner comprising a nozzle adapted to be applied to a surface to be cleaned; a motor driven blower having its suction side connected to said nozzle to direct a stream of air therethrough; filter means to separate dust entrained in said air stream passing through the nozzle and to collect said dust for subsequent removal; a beater mounted adjacent said nozzle for contact with the surface to be cleaned and movable in response to varying pressure in the air stream; and pressure fluctuation means for causing periodic fluctuation of pressure in said air stream whereby said beater may be moved to effect a beating action on the surface to be cleaned.

As has been explained, the invention strongly prefers to use a "tangential" blower. With such a blower the pressure fluctuations are readily produced by arranging a portion of the guide means to move cyclically by reason of forces set up by the air flow through the blower, under the restraint of a spring.

The invention includes a large variety of further features which, with their attendant advantages will be described with reference to specific examples illustrated in the accompanying drawings.

In the drawings:

FIGURE 1 illustrates a vacuum cleaner according to the invention partly in side elevation and partly in vertical longitudinal section;

FIGURE 2 is a vertical transverse section of the FIGURE 1 vacuum cleaner taken on the line II-II in that figure;

FIGURE 3 is a plan of the FIGURE 1 vacuum cleaner;

FIGURE 4 is a plan view of a blower forming part of the FIGURE 1 vacuum cleaner, this view showing how air flow takes place through it in operation and illustrating the Rankine vortex which forms;

FIGURE 5 is a velocity profile occurring in the FIGURE 4 blower in operation thereof;

FIGURE 6 is a velocity profile such as occurs in the prior art;

FIGURE 7 is a diagram illustrative of the Rankine vortex which forms in operation of the FIGURE 4 blower;

FIGURE 8 is a diagram showing an idealized pattern of flow through the rotor of a blower such as that of FIGURE 4, by reason of the Rankine vortex;

FIGURE 9 is a diagram showing the path of a principal flow tube through the rotor of the FIGURE 4 blower and illustrating how it impinges on the rotor blades;

FIGURE 10 is a cross-section of two rotor blades which can be used in the FIGURE 4 blower;

FIGURE 11 is a graph which shows curves of pressure against volume of throughput for the FIGURE 4 blower and for a comparable axial blower;

FIGURES 12 to 15 illustrate nozzle by-pass means which are alternative to that of the FIGURE 1 vacuum cleaner—more specifically;

FIGURE 12 is a plan view corresponding to FIGURE 4 and showing a modified blower;

FIGURE 13 is a partial plan view of a vacuum cleaner showing a modification with respect to that of FIGURES 1 to 4;

FIGURE 14 is a partial vertical longitudinal section of the FIGURE 13 vacuum cleaner, taken on the line XIV-XIV in that figure;

FIGURE 15 is a partial plan view of a vacuum cleaner showing a further modification with respect to that of FIGURES 1 to 4;

FIGURE 16 is a graph showing a curve of pressure against volume of throughput illustrative of the operation of the vacuum cleaners so far described;

FIGURE 17 is a vertical longitudinal section through the nozzle portion of a vacuum cleaner, illustrating a modification which can be incorporated into the vacuum cleaner of FIGURES 1 to 4;

FIGURES 18 and 19 are sections of a blower generally similar to that of FIGURE 4 but incorporating flow control means, each of the two figures showing one of two operative positions of the control means and the flow which takes place;

FIGURE 20 is a view similar to FIGURE 1 of a modified form of vacuum cleaner incorporating a carpet-beating arrangement;

FIGURE 21 is a plan of the FIGURE 20 vacuum cleaner;

FIGURE 22 is a view similar to FIGURE 4 of the blower utilized in the FIGURE 20 vacuum cleaner;

FIGURES 23 and 24 are sections of a blower having a control means operable manually to vary flow conditions, the figures showing two operative positions of the control means and the corresponding flow;

FIGURE 24a is a graph illustrating the operation of what is described with reference to FIGURES 23 and 24;

FIGURE 25 is a plan corresponding to FIGURE 3 of a further modified form of vacuum cleaner including means to direct an air jet at a surface to be cleaned;

FIGURE 26 is a view corresponding to FIGURE 4 and showing the blower of the FIGURE 25 vacuum cleaner;

FIGURES 27 and 28 are vertical longitudinal sections showing alternative means for controlling the air jet in the FIGURE 25 vacuum cleaner; and,

FIGURE 29 is a side elevation of a battery operated vacuum cleaner.

Referring now to FIGURES 1 to 4 of the drawings, the vacuum cleaner therein shown comprises a casing 1 of rounded exterior which is moulded of plastics material.

40 Within the casing 1 at the rear is an electric motor 2 arranged with its shaft (not shown) vertical; the upper end of the shaft carries a bladed cylindrical blower rotor 3 which will be described in detail later. The rotor 3 co-operates with guide walls 4, 5 and upper and lower walls 6, 7; these walls form a diffusing duct 8 receiving air discharged by the rotor and leading it to an outlet 9 in the upper part of the casing 1; a series of vanes 10 which extend across the outlet in a generally longitudinal direction preventing the user's hand or any other sizable object from entering the duct.

The casing 1 is formed on its underside, near the front with a nozzle 12 which extends most of the way across the width of the casing. The rear surface 13 defining the nozzle 12 is continuously and gently rounded and convex thereto: it merges into a convex surface 14 bearing upon the surface to be cleaned (not shown). The front surface defining the nozzle 12 is more complex and includes an upper surface portion 15 diverging from the rear nozzle-defining surface 13 and a lower surface portion 16 which is gently concave towards the surface to be cleaned and spaced only slightly from it. The upper and lower front surface portions 15, 16 merge in a sharply rounded nose 17 situated at narrowest part of the nozzle 12. Just in front of the nose 17 a convergent duct 18 opens into the lower front surface portion 16, to lead air in a generally downward direction towards the surface to be cleaned: the duct 18 extends over the whole length of the nozzle 12. The lowest point 19a of the rear bearing surface 14 is somewhat lower than the corresponding point 19b of the casing surface immediately forward of the nozzle 12.

A dividing wall 20 extends upwardly from the bottom 21 of the casing 1 forward of the motor 2, over the whole width of the casing. A filter designated generally 22 extends across the casing 1 between the dividing wall 20

and the top of the front nozzle surface portion 15, the filter comprises a longitudinally pleated filter paper 23 supported on wires 23a running longitudinally between the dividing wall 20 and the surface portion 15 and located in the pleats of the filter paper.

A shallow dust tray 24 is pivotally mounted at its forward end to the casing member, designated 25, which, having the form of a bar extending across the width of the casing, provides the rear nozzle surface 13 and bearing surface 14: the pivots of the tray are shown at 26, and the tray is shown in full lines in the closed position while chain lines 27 show the open position of the tray. In the closed position of the tray 24, its rear end 28 engages the forward surface of the dividing wall 20, while its sides 29 engage snugly within the side walls 30 of the casing 1. The vacuum cleaner is provided with a handle 31 extending rearwardly and upwardly from a fork the arms 33 of which embrace the rear of the casing 1 and are pivoted to it at 34. The forward extremities of the arms 33 co-operate with leaves 35 at either side of the casing 1 which are articulated to lugs 36 rigid with tray 24, so that the handle 31 can be used to control opening of the tray. The rear ends 37 of the levers 35, which are downwardly bent, engage in notches 38 at the extremities of the arms. In the normal operating position of the arms 33 and tray 24, shown in full lines, the lugs 36 extend upwardly. To move the tray 24 to open position shown by the chain lines 27 the arms 33 are moved down to the position shown in chain lines 39. The lever ends 37, being caught in the notches 38, are displaced rearwardly and rotate the lugs 36, which bring the tray 24 with them. To return the tray 24 to closed condition the handle 31 is moved back to its operating position whereupon the levers 35 cause the tray to move correspondingly. The tray 24 can thus be emptied without touching it.

The vacuum cleaner, as so far described, operates as follows. Operation of the motor 2 causes the blower, which consists essentially of the rotor 3 and the surrounding guide surfaces, to draw in air from the space 40 above the filter 22 and expel it through the duct 8 to the outlet 9, it being understood that the space 40 is always in free communication above the filter and around the motor and guide walls 4, 5, 6, 7 with the rotor inlet arc 41. This air movement causes a flow of dust-entraining air into the nozzle 12 and through the filter 22, the main direction of flow through the nozzle 12 is indicated by the arrow 42, and it will be appreciated that since the lowest point 19b of the front bearing surface lies above the corresponding point 19a of the rear bearing surface 14, the bulk of the air will enter from forwards of the nozzle. The static pressure adjacent the nose 17 will be considerably less than atmospheric, so that a subsidiary stream of air will enter the nozzle 12 through the duct 18 at a good speed. This subsidiary stream of air is directed at that part of the surface to be cleaned which lies directly under the nozzle 12. The increased turbulence at the surface to be cleaned improves the likelihood of a given particle of dust thereon being entrained in the air flow. The subsidiary stream of air is removed with the main stream through the nozzle 12. The air entering through the nozzle 12 impinges obliquely on the filter and is channelled rearwardly by the pleats in the paper 23. Air passes through the filter paper 23 over its whole comparatively large area: air velocity along the pleats diminishes going rearwardly so that dust tends to drop out of the air stream into the dust tray 24 below. This, coupled with the fact that air is continually sweeping over the filter area, rather than impinging upon it at right angles and passing straight through, tends to keep the filter from getting choked with a layer of dust so as to require frequent changing. It is to be noted that in the arrangement described care is taken to avoid contamination of the filter and consequent deterioration of performance, in contrast in particular to conventional arrange-

ments hitherto used where the dust is stored upon the filter surface.

It will be noticed that even if the surface to be cleaned, a carpet for example, blocks flow into the nozzle 12, air can still be drawn through the blower from the duct 18. The significance of this will be explained later.

It is also to be noticed that the casing 1 rides over the surface to be cleaned without wheels, the bottom 21 of the casing, the bottom of the tray 24, and the bearing surface 14 being well rounded for this purpose. One main factor which makes it possible to do without wheels is the relative small size and weight of the motor-blower combination, for reasons which will appear.

The blower of the vacuum cleaner of FIGURES 1 to 15 will now be described in greater detail with reference to FIGURE 4, wherein it is shown in more detail and without other parts, and with reference to FIGURES 5 to 9 which explain its operation and design.

Referring to FIGURE 4, the blower comprises the cylindrical rotor previously referred to and designated generally 3. This rotor has its interior entirely clear of obstruction, and is mounted on the shaft of the motor 2 (the motor being shown only in FIGURE 1) for rotation about its axis at a predetermined speed in the direction of the arrow 52. The rotor 3 is provided with blades 53 extending longitudinally and having inner and outer edges 54, 55 lying on inner and outer coaxial cylindrical envelopes indicated at 56, 57. The blades 53 are concave facing in the direction of rotation, and have their outer edges leading their inner edges.

As has already been mentioned, guide walls 4, 5 are provided which extend the length of the rotor. The guide wall 4 provides a main guide surface 59 which divides the suction region S from the pressure region P. The main guide surface 59 is gently concave with respect to the rotor 3 and converges therewith in the direction of rotor rotation from a nose 60 to a line of nearest approach 61 so as to define with the rotor a converging gap 62. The line of nearest approach 61 lies spaced from the rotor envelope 57 by more than one third of the radial blade depth (in fact by about half), and extends over only a very small arc thereof (in fact it subtends at the axis of the rotor an arc of less than 20°).

The ends of the rotor 3 are closed off by discs (not shown) received in recesses 64, 65 (FIGURE 1) in the upper and lower walls 6, 7 which close off the guide walls 4, 5 as already described.

In operation of the FIGURE 4 blower a Rankine vortex is set up, the core of which is eccentric to the rotor axis, and indicated by the flow lines shown chain dotted at V; the whole throughput flows twice through the rotor blades 53 in a direction always perpendicular to the rotor axis as indicated in general direction only by the chain dotted flow lines F, MF.

FIGURE 7 shows the distribution of velocity in the vortex. The chain dotted line 71 represents a diameter of the rotor taken through the axis 72 of the vortex core V: this line 71 as well as the axis 72 is shown in FIGURE 8. Velocity of fluid at points on the line 71 by reason of the vortex is indicated by the horizontal lines 73a, 73b, etc., the length of each line 73a, 73b, etc., being a measure of the velocity at the point 73a', 73b', etc., respectively. The envelope of these lines is shown by the curve 74, which has two portions, one 74a approximately a rectangular hyperbola and the other, 74b, a straight line. The curve 74a relates to the field region of the vortex and the curve 74b to the core region. The direction of flow within the rotor is shown for the various flow lines F in FIGURE 8, where the core region is shaded, and the remaining flow lines are those of the field region.

The core V of the vortex is a whirling mass of air with no translational movement as a whole, and velocity diminishes going from the periphery of the core to its axis 72. Static pressure along the line 71 is shown by the curve

75: it will be seen that the vortex core V is a region of low pressure. The location of the core region can be discovered by investigation of pressure distribution within the rotor.

It will be understood that the curves are those of an ideal or "mathematical" Rankine vortex and actual flow conditions will only approximate to those curves. In fact, as will be seen, FIGURE 4 does not correspond exactly with FIGURE 8. Although for convenience the vortex core V has been shown circular and has been regarded as possessing an axis, the core will usually not be truly circular.

The velocity profile of the air at the second entrance thereof to the rotor blades will be that of the vortex. In the ideal case of FIGURE 7 this profile will be that of the Rankine vortex there shown by curves 74a, 74b; in an actual case the profile will still have the general character of a Rankine vortex. Thus there will be in the region of the periphery of the core V a flow tube of high velocity indicated at MF in FIGURES 4 and 8 by the heavier chain dots while the flow tubes remote from the periphery of the core will have a very much smaller velocity. On account of the vortex there is at the exit from the rotor 3 a velocity profile such as shown (somewhat exaggerated) in FIGURE 5 where the line PQ represents the exit arc 63 and the ordinates represent velocity. The curve exhibits a pronounced maximum at R which is much higher than the average velocity represented by the dotted line (the average being obtained by dividing the total throughput per unit of time by the area represented by the exit arc 63).

It will be appreciated that much the greater amount of air flows in the flow tubes in the region of maximum velocity. It has been found that some 80% of the flow is concentrated in the portion of the output represented by the line ST, which is less than 30% of the total arc 63. A much smaller arc is in fact all that needs to be considered. A normal velocity profile for fluid flow in a defined passage is shown by way of contrast in FIGURE 6: those skilled in the art will regard this as an approximately rectangular profile. This is the sort of profile which, following the principles generally adhered to in the art hitherto, a designer of a flow machine would aim for in the outlet thereof.

The maximum velocity R as shown in FIGURE 5 applies to a maximum-velocity flow tube indicated in FIGURES 4 and 8 by the heavier chain dots and designated MF. With a given construction the physical location of the flow tube MF is fairly closely defined. Therefore in the restricted zone of the rotor blades 53 through which this flow tube MF passes, the relative velocity between blades and fluid is much higher than it would be in a flow machine which, following the principles adhered to hitherto in the art, was designed for a rectangular velocity profile and uniform loading of the blades in the zones thereof where fluid passes.

One main advantage of the blower described will now be appreciated. As the velocity of the flow tube MF is several times greater than the average velocity (see FIGURE 5), in the restricted blade zones through which the flow tube MF passes there will be much less separation loss than if that tube flowed at the average velocity of throughput; in the flow tube MF, that is, transfer of momentum to the air occurs under excellent conditions. The transfer of momentum in the flow tubes travelling below the average velocity will be poorer, but on balance there is a substantial gain because by far the greater proportion of the throughput is associated with the flow tube MF.

A blower for a domestic vacuum cleaner is necessarily a flow machine operating at low Reynolds numbers. In the past low Reynolds numbers have been associated with unavoidable inefficiency. However in the blower described, despite an overall low Reynolds number, a major portion of the flow is in fact at high Reynolds num-

bers owing to its velocity being far above average. Thus this blower is able to show unexpectedly high efficiencies and in consequence, for a corresponding performance a blower constructed on the principles described above will be smaller and lighter than a comparable axial or centrifugal blower of conventional design.

FIGURE 9 shows the maximum velocity flow tube MF intersecting the envelope 56 at 80, 81. It will be seen that ideally the maximum velocity flow tube MF undergoes a change of direction of about 180° in passing through the interior of the rotor, and that the major part of the throughput (represented by the flow tube MF) passes through the rotor blades where they have a component of velocity in a direction opposite to the main direction of flow within the rotor indicated in FIGURE 9 by the arrow A.

Vector diagrams are shown in FIGURE 9 for the velocities at the points 80, 81. In the diagrams U is the velocity of the inner edges of the blades at the points 80, 20 81 respectively, VA the absolute velocity of the air in the flow tube MF at these points, and VR 1 and VR 2 the velocity of that air relative to the blade at these points as found by completing the triangles. The rotor blade angles can be designed for shock-free flow of the maximum flow tube MF since, as shown above, it flows through narrowly defined zones of the rotor.

It is considered that the blade angles and blade curvature determine the character of the vortex while the position of the vortex core is determined by means of the main guide surface 59. It is considered that in a given case the particular blade angles and blade curvature, depend on the following parameters among others: the diameter of the rotor, the depth of a blade in radial direction, the density and viscosity of the fluid, the dispositions of the 30 external guide body, the rotational speed of the rotor, as well as on the ratio between overall pressure and back pressure. These parameters must be adapted to correspond to the operating conditions ruling in a given case. This teaching is not limited to a particular case but is 40 quite general: nevertheless in a given case the teaching given imposes the adoption of quite definite blade angles and curvature. (Blade curvature is in this connection to be understood to mean not only the curvature of a blade of uniform thickness, but also the curvatures of the contours of profiled blades). Whether or not the angles and curvatures have been fixed at optimum values is to be judged by the criterion that the flow tubes close to the vortex core should be deflected by approximately 180°.

Reverting to FIGURE 4, it will be seen that the guide 50 wall 4 provides a further guide surface 83 merging with the main guide surface 59 at the nose 60. The flow tube MF tends to follow the guide surface 83, just as the vortex core V tends to adjust itself to bring its peripheral flow tube parallel to the main guide surface 59.

The guide wall 5 diverges steadily from the rotor 3 going from a line 84 of nearest approach thereto which lies opposite the main guide surface 59. The line 84 of nearest approach lies spaced more than one third the 60 radial blade depth from the rotor envelope 57, in fact (like the corresponding line 61 of the main guide surface 59) about half that depth. The arcs of entry to and discharge from the rotor 3 divide at the line 84, the former being over 180° in extent.

The preceding discussion will have indicated that the 65 most important guide surface is the main guide surface 59 and that the blower will operate even if the surface 83 and the wall 5 are absent. Although the illustrated configuration of the surface 59 is thought to be the optimum, other guide surface configurations are possible, including a rounded nose and a surface parallel to and spaced from the rotor envelope 57 and defining therewith a parallel gap in contrast to the convergent gap 62 illustrated. In contradistinction to cross-flow machines hitherto proposed, it is strongly preferred that the surfaces 70 which lie close to the rotor 3 should at their nearest ap-

proach be well spaced therefrom: this not only reduces noise and facilitates manufacture, but improves efficiency as well.

The design of the rotor blades 53 is complicated by the fact that each flow tube passes twice over each blade, first inwardly, then outwardly. FIGURE 10 shows one preferred form of rotor blade, which can conveniently be moulded in a plastics material. The blades, here designated 85 are characterized by being thickened adjacent their inner edges: this thickening, besides increasing turbulence, reduce the shock at entry to the blades of the lower-velocity flow tubes. Further increase of turbulence can be obtained by flutings or grooves or other flow-disturbing irregularities at inner and/or outer edges of the blades. One such fluting is shown at 86.

FIGURE 11 shows curves contrasting the operation of a blower such as described with reference to FIGURES 4 to 9 with known vacuum cleaner blowers. The throughput volumes are plotted as abscissae and the suction (pressure below atmospheric) as ordinates. Curve 90 represents the resistance of a given apparatus with clean filter, and curve 91 the resistance of the apparatus with the filter loaded. Curve 92 represents the characteristic (i.e., relationship between pressure and throughput) for a blower as described with reference to FIGURES 4 to 9. The operating range of throughput is shown hatched: the loading up of the filter effects a reduction of throughput as shown at 93 and an increase of suction as shown at 94. The maximum operating pressure is only very little below the maximum pressure 95 of which the blower is capable. By contrast, curve 96 shows the characteristic of a blower of known type: here the operating pressures are far below the maximum pressure 97 which the blower can develop.

It has already been mentioned as one of the appreciations on which this invention is based, that the capacity of a vacuum cleaner to remove dust particles is dependent largely on the throughput. With the known blower, high pressure at the point 97 is nearly useless as the throughput is very small. Yet, it is necessary to use a blower which can produce this pressure in order to have the operating range illustrated.

Now one of the characteristics of the blower according to FIGURES 4 to 9 is that the pressure falls to nearly zero as the throughput drops below that of the maximum pressure point 95. Thus if such a blower were to be mounted in a vacuum cleaner without special precaution and the nozzle were to be blocked, as by some impermeable sheet material, throughput and pressure would fall together, and the vacuum cleaner would for the time being cease to operate effectively. It will usually be desirable to prevent this from happening.

FIGURE 1 illustrates one way to prevent the throughput from falling unduly. Thus, the duct 18 provides a by-pass for air flow towards the rotor 3 when the mouth of the nozzle 12 is blocked by a carpet or the like. This in fact is the primary object of the duct 18; its turbulence-creating effect is valuable, but secondary.

Alternative nozzle by-pass arrangements are shown in FIGURES 12 to 14. Thus, should it be desired to dispense with the by-pass duct 18 of FIGURE 1, the diffusing outlet duct 8 of that figure could be replaced by the diffusing outlet duct 100 of FIGURE 12 which is perforated, as shown at 101, in those regions where separation of the boundary layer is likely to occur; in other respects the vacuum cleaner remains similar to that of FIGURE 1. In operation, when the nozzle 12 (not shown in FIGURE 12 but illustrated in FIGURE 1) becomes blocked the pressure in the space 40 drops: this is the pressure immediately outside the perforated diffusing duct 100, so that the boundary layer is sucked out through the holes 101 and recirculates through the rotor 3. The walls of the duct 100, or parts of them, can be made of fabric.

A generally similar effect can be obtained with an inlet duct on the suction side of the rotor 3 downstream of

the nozzle, as shown at 103 in FIGURES 13 and 14: it is to be understood that these figures show only the rear portion of a vacuum cleaner which is generally similar to that of FIGURES 1 to 3 except as regards the omission of the duct 18 shown therein and the presence of the duct 103. Similar parts are given the same reference numerals and will need no further description.

The duct 103 is formed as a slit in the rear wall 104 of the casing 1, a lower portion 105 of this wall overlapping an upper portion 106 thereof in outwardly spaced relation thereto. When the nozzle of the vacuum cleaner is blocked the pressure drops in the space 107 between the motor 2 and the rear casing wall 104, and air flows into that space through the duct 103 so as to provide throughput to the rotor 3, the inward flow being opposite in direction to the flow through the space 107. The duct 103 is designed so that in normal operation there is a balance between the dynamic pressure of the air in the space 107 which flows up to the rotor 3, and the difference between the static pressure in the space 107 and the ambient pressure: thus in normal operation there is negligible flow through the duct 103.

If it is required to increase the flow velocity in the space 107, partition walls 108 may be formed in the casing 1 between the side walls 30 thereof and the motor 2 and guide walls 4, 5, so as to constrain all the air from the space 40 to pass around the lower part of the motor.

The FIGURE 15 bypass arrangement comprises a duct 110 at the narrow end of the diffusing outlet duct 8 and providing communication between the latter duct and the space 40. The guide wall 4 is made in two parts 111, 112, the first providing the main guide surface 59 and an initial portion of the guide surface 83; the second guide wall part 112 provides the remainder of the surface 83 and overlaps the part 111 in outwardly spaced relation to form a part of the duct 110. The guide wall 5 is similarly divided into two parts 113, 114 which overlap to provide a further part of the duct 110. The upper and lower duct walls 6, 7 are similarly divided, so that the duct 110 extends all around the duct 8.

The bypass duct 110 is substantially inoperative when the vacuum cleaner nozzle 12 is open, but when the nozzle becomes blocked the pressure in the space 40 drops and air is drawn into it from the duct 8 through the duct 110, and this air is recycled through the rotor 3 to maintain, to some degree, the throughput of the blower.

Once again it is to be assumed that the FIGURE 15 vacuum cleaner resembles that of FIGURES 1 to 3 except for the substitution for the bypass duct 18 of the duct 110.

The effect of the nozzle bypass arrangements of FIGURES 1 to 3, 12, 13, 14 and 15 is illustrated in FIGURE 16, in which values of throughput through the nozzle 12 are plotted as abscissae, and pressure values as ordinates.

The curve 120 illustrates the relation of pressure and throughput for the blower of FIGURE 4 without a bypass arrangement, and the dotted line 121 shows the effect of introducing the bypass. The curve 120 shows how, without the bypass, progressive blockage of the nozzle and consequent decline in blower throughput causes a characteristic fall in pressure from the maximum 122 to a low value. (This characteristic pressure fall has been mentioned earlier in connection with FIGURE 11.) By contrast, with a bypass arrangement the blockage of the nozzle does not cause more than a slight drop of blower throughput so that, as shown by curve 121, pressure is substantially maintained. This enables the vacuum cleaner to continue functioning efficiently despite occasional partial or complete blockages of the nozzle thereof.

It is to be understood that the various nozzle bypass arrangements can be used in various combinations if desired. Various further bypass arrangements are discussed with reference to later figures.

FIGURE 17 shows a modification of the front portion 75 of the vacuum cleaner of FIGURES 1 to 3: it is to be as-

sumed that the parts of the vacuum cleaner not illustrated in FIGURE 17 are substantially similar to those of FIGURES 1 to 3.

FIGURE 17 shows a nozzle designated generally 130 having a series of projections 131 about the nozzle mouth 132; restricted air inlet openings are provided between adjacent such projections. The vacuum cleaner casing, here designated 133 provides a wall 134 at the left hand side of the nozzle 130, which is thickened as shown at 135 and there formed with an opening 136 closable by a pivoting flap 137. The friction at the pivot of the flap 137, indicated at 137a, is such that the flap can readily be adjusted by hand, but will remain in adjusted position in normal use of the vacuum cleaner. In the closed position of the flap 137 (shown in chain lines) its inner surface 138 fairs more or less with the rest of the interior of the nozzle: this position is suitable for cleaning material that is readily air-permeable, for example lightweight curtains—in such use the throughput will never be unduly reduced. The position is also suitable for cleaning a rigid surface such as a floor which cannot close up the inlet openings between the projections 131. For nonpermeable and semipermeable flexible materials the flap 137 is opened: the best opening for any material to be cleaned can be found by experiment. When the flap is open, the outer surface 139 thereof defines with the opposed side 140 of the opening 136 a convergent duct leading air downwards to the nozzle mouth 132 as shown by the arrows 141: it will be understood that air enters the opening 136 because, as entry of air past the projections 131 is restricted, the interior of the nozzle is a zone of low pressure. The air entering the opening 136 has a high velocity on account of the converging of the surfaces 139 and 140 between which it enters (as is also the case of the duct 18 of FIGURE 1), and it impinges on a portion 142 of the surface 143 to be cleaned at the middle of the nozzle mouth 132. This creates a powerful whirling or disturbance of the dust as indicated at 144, the disturbance tending to extend over the whole area of the nozzle mouth 132 by reason of the angle at which the air enters the opening 136.

The effect of the air entering the opening 136 at the angle shown is to obviate sluggishness in the removal of dust due to laminar flow in the nozzle mouth 132 as previously referred to. It will be seen that the general configuration of nozzle 130 and opening 136, with the flap 137 positioned as shown, is generally similar to that of the nozzle 12 and duct 18 in FIGURE 1: the two arrangements operate similarly as regards the stirring up of dust, and the provision of a bypass to maintain rotor throughput should the nozzle become blocked. As above mentioned, in contrast to that of FIGURE 1, the FIGURE 17 arrangement provides for closing the bypass in the special cases where the surface to be cleaned is such as to be incapable of blocking the nozzle.

As previously explained in a blower such as described with reference to FIGURES 4 to 9 the throughput and pressure depend on the character of the vortex and its location with respect to the rotor blades, and this in turn depends on the character and location of the main guide surface, designated 59 in FIGURE 4. FIGURES 18 and 19 show a modified blower construction in which the effective main guide surface can be altered, to vary the throughput and pressure.

The blower of FIGURES 18 and 19 makes use of a rotor similar in all respects to the rotor 3 of FIGURE 4: the same reference numerals will be used for corresponding parts which will need no further description. The blower of FIGURES 18 and 19 employs a guide wall similar to the guide wall 5 of FIGURE 4, and similarly designated, but instead of the wall 4 thereof the vortex-stabilizing arrangement takes the form of a guide body designated generally 150 extending the length of the rotor 3 opposite the wall 5 and defining therewith the outlet duct here designated 151.

The guide body 150 comprises a fixed portion 152 presenting a wall surface 153 to the duct 151 which surface is continued towards the blower in a wall 156 of sheet material whose free end portion is spaced somewhat from the rotor. The guide body 150 further comprises an auxiliary body 158 which is generally triangular as seen in section and is pivoted about an axis parallel to one edge of the wall 156 so that its curled end portion 157 forms a continuation of the end of wall 156 on the entry side thereof, the pivot axis being indicated at 159. The body 158 has one concave side 160 opposite the rotor. In the FIGURE 18 position of the body 158 the concave side 160 thereof converges towards the rotor 1 in the direction of rotation by way of continuation of the curled end portion 157 of the body 158: thus a wedge-shaped space 161 is formed between the surface 160 and rotor 3 and a vortex core is consequently set up as shown at V. In the FIGURE 19 position the body 158 is retracted behind the wall 156 and is inoperative; in this position the vortex is formed at the curled portion 157 of the body 158 as shown. Thus the vortex core is displaced towards the outlet.

In the FIGURE 18 arrangement the configuration of the flow guiding surfaces is generally similar to that of FIGURE 4, and the main guide surface is the surface 160: the FIGURE 19 arrangement is different and the main guide surface is the curled tip 157 of the body 158. The FIGURE 18 arrangement produces a bigger vortex core, and is quieter, but produces less throughput. The construction may thus be used normally in the FIGURE 18 arrangement, and the body 158 moved to the FIGURE 19 position when the character of the surface to be cleaned requires extra throughput.

FIGURES 20 to 22 show a modification of the vacuum cleaner of FIGURES 1 to 3, designed to produce a beating effect on a carpet 169 to be cleaned. Parts which correspond to those of FIGURES 1 to 3 are given the same numerals and will need no further description.

The vacuum cleaner of FIGURES 20 to 22 has no duct 18 opening into the nozzle 12, as in FIGURE 1, but instead employs the perforated-diffuser bypass arrangement described with respect to FIGURE 12.

Instead of the dust tray, here designated 24', being pivoted at its forward end it is pivoted to the side walls 30 of the casing 1 by means of lugs 170 adjacent its rear end. The sides of the tray 24' fit snugly within the casing walls 30 as shown in FIGURE 2; the forward end of the tray is adapted to slide with minimum friction over a correspondingly-shaped surface 171 of the casing member 25 so as to form a substantially airtight joint therewith, and the rear edge of the tray carries a rubber bead 172 in sealing relation with the casing wall 20. The tray 24' is connected adjacent its forward end with the casing by means of a spring 173. The tray 24' is thus capable of oscillation under the influence of pulsating air pressure in the space above it.

To empty the tray 24' of dust the spring 173 is disconnected from the tray which is then pivoted downwardly by hand. The emptying arrangement of FIGURE 1 is not employed to the vacuum cleaner of FIGURES 20 to 22.

Pulsating pressure in the space above the tray 24' is produced by the blower shown in FIGURE 22. This blower employs a rotor 3 and guide wall 5 similar to those of FIGURE 4, similar references denoting similar parts. However, in place of the guide wall 4 of FIGURE 4 there is provided a guide means designated generally 174 extending the length of the rotor between upper and lower walls (not shown in FIGURE 22) and comprising a main body 175 which is fixed and an auxiliary body 176 which is pivoted about the axis 177 and connected thereto by a spiral spring 178. Comparing this arrangement with that of FIGURES 1 to 4, it will be seen that while the main body 175 provides a fixed guide surface 179 corresponding to the surface 83 (FIGURE 4) it is the

auxiliary body 176 which provides the main guide surface here designated 180 which corresponds to the surface 59 of FIGURE 4, and that unlike the surface 59, the surface 180 is movable relative to the rotor.

In operation, the auxiliary body 176 performs weakly damped oscillations under the influence of forces set up by the moving air, and under the control of the spring 178. From the foregoing it will be appreciated that movement of the main guide surface (here shown at 180) effects the vortex and hence the pressure and throughput produced. Thus the oscillations of the body 176 cause pressure pulsations which, by their effect on the tray 24' cause it to move up and down and thereby produce a beating effect on the carpet 169. This effect is enhanced by raising the mouth of the nozzle 12 as compared with FIGURE 1: the carpet 169 will tend to lift to the nozzle, and the tray 24' will periodically agitate the lifted part of the carpet.

FIGURES 23, 24 and 24a illustrate a further modification of the vacuum cleaner of FIGURES 1 to 3. It is to be assumed that the modified blower of FIGURES 23 and 24 is incorporated in FIGURES 1 to 3 in place of the FIGURE 4 blower, without other modifications. Parts in FIGURES 23 and 24 which correspond with parts of the FIGURE 4 blower are given the same references and will need no further description.

Once again it will be seen that the blower of FIGURES 23 and 24 employs a rotor 3 and guide wall 5. However the guide wall 4 of FIGURE 4 is replaced by adjustable guide means. These guide means include a rigid wall 190 opposite the wall 5, and a generally triangular-sectioned movable body 191 pivoted to the wall 190 by means of a sheet of rubber 192 which is secured thereto in overlying relation and which is secured also to the body 191; the sheet of rubber 192 is recessed into a guide surface 193 of the body 191 and provides a fairing between it and that surface in all positions of the body 191. The guide surface 193 lies opposite the guide wall 5, and merges at a rounded nose 194 into a further guide surface 195 which lies opposite the rotor 3. A strip 196 of rubber is secured at one edge to a bar 197 lying parallel to the rotor and somewhat spaced therefrom so that the opposite edge 198 of the strip, which is bevelled, presses against the guide surface 195 in all positions of the body 191. By means of a lever 199 the body 191 can be moved between the positions shown in FIGURES 23 and 24. In the FIGURE 23 position of the body 191, the rubber strip 196 and the upper part of the body surface 195 combine to form a main guide surface corresponding to the surface 59 of FIGURE 4, but of greater extent: the vortex core V which forms is of large size. In the FIGURE 24 position of the body 191 the main guide surface is provided solely by the rubber strip 196 the upper edge 198 of which touches the body at the nose 194 thereof: the extent of the main guide surface is small, and the vortex core V is correspondingly small. The throughput of the blower is much greater in the FIGURE 24 position of the body 191.

FIGURES 23 and 24 illustrate only diagrammatically the mechanism for moving the body 191. The lever 199 connected thereto is articulated to a rod 200 extending from one end wall 201 of a bellows 202 having its other end 203 fixed and its interior connected to a squeeze bulb 204 mounted on the vacuum cleaner in any convenient position, e.g., the top of the handle 33. The bellows 202 has a bleedoff of predetermined size, shown by the capillary 205. When the bulb 204 is squeezed by hand, the bellows 202 expands and brings the body 191 from its normal position shown in FIGURE 23 to its FIGURE 24 position. Release of the bulb 202 returns the body to the FIGURE 23 position. If the bulb 204 is kept squeezed, the body will return slowly to the FIGURE 23 position by reason of the bleed capillary 205.

FIGURE 24a illustrates the operation of what has been described with reference to FIGURES 23 and 24.

This figure shows a curve 210 of efficiency (η) against throughput (ϕ), and a curve 211 of power taken (N) against throughput: efficiency and power are represented as ordinates, and throughput as abscissae. The normal operating point is shown at 212. Now reducing the throttling as described brings the operating conditions to the point 213. The throughput is much increased and so is the power taken, while the efficiency is about the same. The increase in throughput corresponds (as previously explained) to increased ability to pick up dust, the increase in power consumed is accounted for over a short period by the kinetic energy stored in the motor-rotor combination, which in this case is preferably provided with a flywheel. Operation for any appreciable time at the point 213 would lead to damage of the motor through overload. It is for this reason the bellows 202 is provided with the bleed 205.

Instead of pivoting the body 191 to control the blower, a similar control can be exercised by pivoting the guide wall 5 about an axis at its line of nearest approach to the rotor.

The arrangement shown enables the sucking ability of a vacuum cleaner to be momentarily increased under convenient manual control, for example to pick up a thread on a carpet.

The FIGURE 1 nozzle (reference numeral 12) is provided with a duct 18 through which a stream of air enters from the surrounding atmosphere and stirs up dust directly under the nozzle to facilitate its being sucked in. FIGURES 25 to 27 show a vacuum cleaner in which a stream of air for this purpose is supplied from the blower. Parts of the vacuum cleaner which correspond to parts described with reference to FIGURES 1 to 3 are given the same reference numerals and will not be discussed. The front of the vacuum cleaner (FIGURES 25 and 27) is formed with a duct 220 in the thickness of the casing 1 which leads from a point 221 towards one side of the upper part of the casing down to the nozzle 12 which it enters similarly to the duct 18 of FIGURE 1: the duct fans out from the point 221 so as to enter the nozzle over the whole length thereof. The duct 220 is supplied with air from a blower shown in detail in FIGURE 26 and which differs somewhat from that illustrated with particular reference to FIGURE 1. This blower makes use of a rotor 3 and guide wall 5 similar to those of FIGURE 1, but for the guide wall 4 substitutes vortex-stabilizing means in the form of a main and an auxiliary guide body 222, 223 respectively, the peripheral flow tubes of the vortex core V circulating around the latter. The side of the main guide body 222 facing the guide wall 5 fairs into a side wall 224 diverging with respect thereto. The outlet duct defined between the walls 224 and 5 is subdivided by curved partition walls 225, 226 and 227 into three large channels 228, 229, 230 receiving the slower flow tubes from the rotor 3 and discharging through the outlet 9, and a separate channel 231 leading past the outlet into the duct 220, and fairing thereinto at the point 221. The purpose of dividing flow to the outlet 9 is to reduce losses in the conversion of kinetic to pressure energy due to the widely different velocities at which the different stream tubes enter the diffusing outlet duct. The function of the channel 231 is to collect the fastest-flowing stream tubes adjacent the vortex core V (in this case a minor proportion of the total flow) and to feed this air stream to the duct 220 where a partial conversion of the kinetic energy to pressure occurs.

The recycling to the nozzle 12 of a minor proportion of the total rotor throughput provides a by-pass flow when the mouth of the nozzle is blocked by the surface to be cleaned, and so enables the blower to maintain adequate suction, as previously explained.

It is undesirable that a stream of air should continue to pass out of the duct 220 when the vacuum cleaner 75 is lifted off the carpet, since this would tend to scatter

dust. To close the duct 220 under these conditions a portion 232 of it adjacent the point 221 is made of resilient material such as rubber; the cranked upper end 233 of a vertical rod 234 slidably mounted in the casing 1 overlies the flexible duct portion 232 while the lower end of the rod is connected to the upper side of a diaphragm 235 fixed in the casing 1 above the filter 22. When the vacuum cleaner is lifted off the floor, the pressure rises in the space above the filter 22, the diaphragm collapses, and the rod 234 slides down to pinch off the duct portion 232.

An alternative method of blocking the duct 220 is shown in FIGURE 28: here instead of the diaphragm 235 the rod 234 is connected to a castor 236 which in normal operation runs over the surface to be cleaned and holds the cranked end 233 of the rod 234 off the flexible duct portion 232. The rod 234 drops and pinches the duct portion 232 shut under the influence of the tension spring 237 when the castor 236 comes off the ground.

FIGURE 29 illustrates a miniature vacuum cleaner having all the features illustrated in FIGURES 1 to 3, except that they are on a smaller scale. The various parts are designated by the same numerals as used in FIGURES 1 to 3, and will not need further description. However, in place of connecting the motor 2 to a main supply, the casing 1 is extended rearwardly and provided with a detachable end portion 460 to accommodate, and provide for access to, a battery 461 supplying power for the motor.

We claim:

1. A vacuum cleaner comprising a handle and a cleaner head adapted to be pushed over a surface to be cleaned, said cleaner head having a casing with an upper surface and substantially flat bottom surfaces adapted to slide over the surface to be cleaned, a motor in said casing, a blower of the cross-flow type in said casing attached at one end to the shaft of said motor with said blower having a drum-shaped bladed rotor, said rotor being vertically positioned in said casing wherein the longitudinal axis of said blower is vertical, a nozzle in said casing adapted to slide over the surface to be cleaned and being connected to the suction side of said blower, an outlet in the upper part of said casing connected to the outlet of said blower and being at substantially the same height as the end of said blower opposite said motor so that the over-all height of said cleaning head is substantially equal to the over-all height of said motor and attached blower, collection means in said cleaner head for collecting dust for subsequent removal from said cleaner head, filter means in said cleaner head to separate dust entrained in the air passing through said nozzle, and nozzle bypass means through which air flows to the rotor unaffected by the surface to be cleaned when resistance to air flow through the nozzle exceeds a predetermined level by reason of the conjunction of said surface to be cleaned with the nozzle whereby throughput of air through said rotor is maintained independent of air flow through said nozzle.

2. A vacuum cleaner as claimed in claim 1 wherein the nozzle bypass means includes a duct adjacent said nozzle leading from ambient atmosphere to the suction side of said blower.

3. A vacuum cleaner as claimed in claim 2 wherein the opening of said duct leading to the inlet of said blower is positioned adjacent said nozzle to direct air passing through said duct onto that portion of the surface to be cleaned which lies beneath the nozzle.

4. A vacuum cleaner as claimed in claim 1 wherein the nozzle bypass means includes a duct leading from the delivery side of said blower to the suction side thereof.

5. A vacuum cleaner as claimed in claim 1 wherein said nozzle bypass means includes a duct opening on the suction side of said blower for passage of air from the ambient atmosphere to the blower and wherein the opening of said duct leading to said suction side opposes the direction of air flow from the nozzle to the blower, where-

by under normal operating conditions the dynamic pressure of air moving from said nozzle to said blower opposes flow of air through said duct, and whereby when said dynamic pressure drops, air will flow through said duct to said blower.

6. A vacuum cleaner as claimed in claim 1 having in addition a diffuser positioned at the outlet of the blower to receive air therefrom, said diffuser being perforated with the perforations in pressure communication with the suction side of said blower whereby air is removed by the boundary layer suction effect from within the diffuser and is recycled to the suction side of the blower.

7. A vacuum cleaner as claimed in claim 1 wherein said filter means is located within the air stream passing from said nozzle to said blower.

8. A vacuum cleaner as claimed in claim 7 wherein said filter means is positioned above said collection means whereby dust-entrained air impinges upon the bottom of said filter and falls therefrom into said collecting means.

9. A vacuum cleaner as claimed in claim 8 wherein said collection means comprises a tray located adjacent said nozzle.

10. A vacuum cleaner as claimed in claim 9 wherein said tray is pivotally connected at one end to said vacuum cleaner whereby its other free end may move between dust-catching and dust-releasing positions.

11. A vacuum cleaner as claimed in claim 10 wherein said filter means is pleated to increase its effective area, said pleats extending in a direction to guide air passing from said nozzle over said collection means.

12. A domestic vacuum cleaner comprising a handle and a cleaner head to be pushed over a surface to be cleaned: the cleaner head having a casing with smooth outer surfaces including bottom surfaces adapted to slide over the surface to be cleaned and providing a nozzle adapted to be applied to a surface to be cleaned; a motor driven blower in the casing having its suction side connected to said nozzle and arranged to draw a stream of dust-entraining air through said nozzle, said blower having a vertically positioned drum shaped bladed rotor and guide means including a guide wall extending the length of said rotor and cooperating with said rotor to form a cylindrical vortex when said rotor is rotated having a general characteristic of a Rankine vortex which vortex is eccentric to the rotor axis and which guides air twice through the path of the rotating blades in a direction transverse to the rotor axis; a motor connected to the lower end of said rotor; an outlet in the upper part of said casing connected to the outlet of said blower and being at the same height as the upper end of said rotor; large area dust filter means located in said casing between the nozzle and the blower to separate dust entrained in the air stream passing through the nozzle; dust collection means within the casing and beneath said filter means, the casing having a removable portion substantially flush with said bottom surfaces for subsequent removal of collected dust; and nozzle bypass means in said casing through which air flows to the rotor unaffected by the surface to be cleaned when the resistance to air flow through the nozzle exceeds a predetermined level by reason of the conjunction of said surface with the nozzle whereby throughput of air through said rotor is maintained independent of air flow through said nozzle; the over-all height of said cleaner head being substantially equal to the over-all height of said motor and attached rotor.

13. A vacuum cleaner as claimed in claim 12, wherein the nozzle bypass means includes a smoothly convergent duct adjacent said nozzle and leading from ambient atmosphere, the duct being directed on to that portion of the surface to be cleaned which lies beneath the nozzle and entering the nozzle at a point spaced from that surface so that air flowing through the duct becomes turbulent within the nozzle.

14. A vacuum cleaner as claimed in claim 13, wherein the duct enters the nozzle substantially centrally thereof

17

as considered in longitudinal vertical sections through the
cleaner head.
